ADJUSTABLE ARCH SUPPORT

Walter H. Hubbard, Beverly, Mass.

Application September 28, 1936, Serial No. 102,930

6 Claims. (Cl. 36—71)

This invention consists in an arch support having adjustable pad members which may be freely positioned to meet the requirements of the individual foot and then fixed in their adjusted positions. No two feet are exactly alike and therefore supporting pads built into shoes as permanent fixtures are wrong in principle and unless individually fitted are as likely to harm as to help the wearer. The support of my invention is designed to underlie the foot and to have component pad members which may be relatively adjusted within a wide range and with a high degree of flexibility to selected locations beneath the foot. For example, one component of my novel arch supporter consists in a pad designed to support the metatarsal arch which is adjustable both longitudinally and angularly so that it may be located exactly under the particular metatarsal head which requires support in the foot under consideration. Another component part of the support consists in a pad for supporting the longitudinal arch of the foot and this is arranged for longitudinal adjustment and for adjustment as to height. Further, and as herein shown, the longitudinal arch may be combined or not as desired with an extension wing for fitting and supporting the inside shank of the wearer's foot.

The various parts above enumerated are assembled and adjustably incorporated in the support and when once properly positioned may be secured permanently in place. To this end the support of my invention includes a flexible sock lining blank to the under side of which is attached a flexible metal strip and upon this the pad members are movably mounted. One satisfactory manner of holding them permanently in adjusted position consists in providing the under face of the sock lining with a coating of adhesive which may be temporarily protected by a cover sheet. When this is removed the adhesive is effective to unite the various pads of the support to the under face of the sock lining thus holding them securely in adjusted position.

The novel arch support of my invention presents many important advantages not realized in other supports heretofore available. It may be fitted by the wearer or the shoe salesman to meet the requirements of the individual foot, and may be refitted to accommodate changed conditions in the shoe or the foot. It is of light weight and so overcomes the objection to metal supports. It does not injure the shoe in which it is worn and can be shifted from one pair to another. By its flexibility of adjustment it may be advantageously employed for a foot not con-

forming to any of the present conventional standards, as for example, a foot in which the metatarsal arch is located as in a size 7 foot and the longitudinal arch as in a size 8 foot, or mis-mated feet. 5

These and other features of the invention will be best understood and appreciated from the following description of a preferred embodiment thereof selected for purposes of illustration and shown in the accompanying drawing, in which, 10

Fig. 1 is a plan view of the support,

Fig. 2 is a view of the support as seen from the under side, and

Fig. 3 is a view in perspective of the parts which are assembled in making up the longitudinal pad. 15

Fig. 4 is a fragmentary view of the metal strip.

Fig. 5 is a cross sectional view of a longitudinal pad of modified design.

The pad illustrated comprises a blank 10 of thin flexible leather shaped to fit the inside of a shoe as a sock lining, and to extend substantially to the ball line. A thin flat metal strip 11 is secured to the under side of the blank 10 at its rear end by flattened eyelets or rivets 12 which are spaced so as to clear the os calcis bone of the wearer's foot. It will be noted that the strip 11 extends continuously to the rear end of the blank 10 and accordingly serves to hold it always in a flat condition during wear and prevent it from curling up. The strip 11 is flexible in flat-wise bending but practically inflexible to edgewise bending and is located preferably in line with the longitudinal axis of the sock lining. 20

The longitudinal pad comprises a semi-circular pocket 13 of leather or the like which is open at its outer edge for the reception of a semi-circular pad 14 of felt or the like. The pad 14 is interchangeable with similar pads of varying thicknesses so that by inserting the appropriate pad or pads like shims in the pocket 13 the effective height of the longitudinal arch may be regulated. The third member of the longitudinal pad comprises a molded leather piece 15. This has a semi-circular portion shaped to fit within the pocket 13 and an upwardly curving wing adapted to fit the inner longitudinal arch curve of the wearer's foot. It may be employed or not as desired in connection with the longitudinal pad and is shown in its operative position in Fig. 1. The pocket 13 is provided with a pair of spaced parallel slots to receive the metal strip 11 and with a diamond shaped opening 16 through which are rendered visible the figures of a size scale 17 which is placed on the under surface of the strip 11. It will be understood that in fitting the sup- 25

port, the longitudinal pad may be slipped back and forth on the metal strip 11 until it accurately supports the longitudinal arch of the wearer's foot, the scale 17 thereupon indicates its position in terms of shoe sizes.

5 The metatarsal pad 18 is roughly triangular or oval in outline and built up to the proper thickness from superposed layers of felt, rubber or the like and a leather backing. The leather backing 10 is slitted to receive the end of the metal strip 11 which thus passes into the interior of the pad, its end lying between the component layers thereof. The pad is adjustable lengthwise upon the strip 11 which may be slipped various distances 15 through the slit. The friction of the strip in passing through the slit is sufficient to hold the pad in whatever position of adjustment it may be set thereon. The strip is provided with a second scale 19 for indicating the lengthwise position 20 of the metatarsal pad and, as shown in Fig. 2, the scale indicates that the pad has been adjusted for a size 7 foot, although it will be understood that the position of the pad is determined from the foot to be fitted and not from 25 the scale or the shoe. The pad 18 may be made in right and left shapes for right and left foot supports.

30 The pad 18 is also arranged for angular or transverse adjustment upon the end of the metal strip 11, as indicated in dotted lines in Fig. 2, so that it may be located beneath any one of the five metatarsal heads on the foot. This adjustment may be made about an axis intersecting the slot in the under side of the pad. The forward 35 end of the strip 11 is longitudinally slitted and the arms thus formed are turned at right-angles and sharpened to form a pair of downwardly extending prongs which tend to hold the pad in position once it has been adjusted by sticking into 40 the material thereof. The prongs are clearly shown in the forward end of the strip 11 as represented in Fig. 4.

45 The under face of the blank 10 is provided with a coating of adhesive 21 and this may be covered temporarily by sheet material 20, such as Holland cloth, which may be stripped from the under side of the blank after the pads have been adjusted so that the blank may be made to adhere 50 to the pads and hold them permanently in position. A cement of the character of latex which preserves its tacky characteristics for a long time is satisfactory for this purpose and may, if desired be stripped and reused more than once if necessary. Alternatively the upper face 55 of the pads may be coated with adhesive and temporarily protected instead of the under face of the blank 10.

60 In Fig. 5 is shown a modified form of longitudinal pad in which the upwardly curving wing is formed as an integral part of the pocket. In this case the cover portion 21 of the pad is substantially circular or oval in outline. Approximately one half constitutes the upper cover of the pocket 22 while the other part is curved to fit 65 the inner longitudinal arch surface of the wearer's foot. The pocket 22 is, as before, open at its outer edge so that filler pads of different thicknesses may be inserted as required. It will be understood that the pad shown in Fig. 5 may be threaded upon the flexible metal strip 11 and provided with an opening shaped to act as a gauge line in cooperation with the longitudinal scale.

70 The forward and side edges of the blank 10 75 may be skived to avoid the formation of ridges

under the foot of the wearer. A graduated series of curves, indicated in Fig. 2 by the figures 10, 9, 8 etc. may appear on the surface of the Holland cloth, indicating where the blank 10 should be cut in adapting for smaller sizes, and the side edges of the blank may be also trimmed if necessary.

10 From the foregoing description it will be seen that I have provided an arch support which may be supplied and kept in stock in perhaps three sizes, for men, women and children, and which will serve to fit accurately the feet of the individual wearer, taking care of whole sizes, half sizes or any fraction of a size by its adjustable features.

15 The support herein shown, moreover, may be fitted accurately to any foot needing both metatarsal and longitudinal arch support. For such use the support consists of a flexible sock lining having a thin flexible metal strip, which in itself 20 is of no arch supporting value, and upon which is plainly and accurately marked both the metatarsal and longitudinal size scale. Adjustably threaded on this metal strip are both metatarsal and longitudinal arch units. Alternatively the 25 arch support can be fitted accurately to any foot needing support in the longitudinal arch only. For this purpose the metatarsal pad and the part 30 of the metal strip that is used for metatarsal adjustment and the surplus forepart of the sock lining may be eliminated. Still further the arch support can be fitted accurately to any foot needing metatarsal arch support only, and when used for this purpose the longitudinal unit may be 35 removed from the assembly.

Having thus described my invention, what I claim as new and desire to secure by Letters Patent is:—

1. An adjustable arch support comprising a flexible sock lining having an adhesive under 40 face, a flat strip underlying the sock lining and being flexible in flat-wise bending and two separate pads mounted on said strip beneath the sock lining for independent adjustment to selected 45 locations beneath the foot of the wearer and adapted to be retained in their adjusted positions by attachment to said adhesive face of the sock lining.

2. An adjustable arch support comprising a flexible sock lining having an adhesive under 50 face, a flexible metal strip secured to said sock lining and extending beneath its adhesive face, and two pads both carried by said strip and separately adjustable thereon to selected positions beneath the foot of the wearer, and when so adjusted being held in position by the adhesive 55 face of the sock lining.

3. An adjustable arch support comprising a flexible foot-shaped blank having a flat metal strip secured to its under side at one end only, a longitudinal arch pad threaded upon said strip and adjustable thereon and having one side open for the reception of a filling pad, the strip being provided with a scale to indicate the position of the pad in terms of shoe sizes, and means for 60 fixing said pad in its adjusted position.

4. An adjustable arch support comprising a foot-shaped cover sheet having an adhesive under 70 face covered with Holland cloth, a flexible metal strip secured to the cover sheet at its rear end and extending forwardly beneath the same, a metatarsal arch pad mounted on the forward end of said strip for longitudinal and transverse adjustment, and a longitudinal arch pad also mounted on the said strip for adjustment, both 75

of said pads being adapted to be held permanently in their adjusted positions by the adhesive upon removal of said Holland cloth covering.

5. An adjustable arch support comprising a sock lining piece having a thin flat metal strip disposed beneath its longitudinal axis and carrying a scale of shoe sizes on its exposed face, a longitudinal arch pad slotted to receive said strip, having an opening in its lower face through which said scale is exposed to view and an opening in its outer edge, and a removable member having an upwardly curved wing extension shaped

to be inserted in the edge opening of said pad.

6. An adjustable arch support comprising a sock lining piece having a thin flat metal strip secured beneath it and forked at its forward end to present a down-turned prong, a metatarsal pad adjustable longitudinally and laterally on the end of said strip, and a longitudinal pad adjustable upon the intermediate part of said strip, an adhesive surface being interposed between said pads and sock lining.
